SHOTGUN CHOKE

William F. Cobb, Utica, N. Y.

Application April 5, 1950, Serial No. 154,151

3 Claims. (Cl. 42—79)

1

This invention relates to chokes of the adjustable type for controlling the pattern of shot charges expelled from a shotgun.

The invention has as its object a choke of the type referred to embodying a simplified structure consisting only of two parts, so designed that they are particularly economical to manufacture, and whereby one part can be quickly and conveniently adjusted to effect all types of shot patterns to and including a full choke.

The invention consists in the novel features and in the combinations and constructions hereinafter set forth and claimed.

In describing this invention, reference is had to the accompanying drawings in which like characters designate corresponding parts in all the views.

Figure 1 is top plan view of a choke structure embodying my invention.

Figure 2 is a sectional view taken on line 2—2, Figure 1.

Figure 3 is a side elevational view of the control sleeve.

Figure 4 is an end elevational view looking to the right, Figure 3.

Figure 5 is an enlarged fragmentary sectional view of the forward end portion of the supporting sleeve.

The structure consists of an outer supporting sleeve 10 and an inner pattern control sleeve 11. The supporting sleeve is internally threaded at its rearward end for threaded attachment to the muzzle of the shotgun barrel 12, and may be secured in fixed position, as by a small set screw 13. The forward portion of the supporting sleeve has a bore larger than the bore of the shotgun barrel 12 and is provided intermediate its ends with internal threads to receive the rear externally threaded portion 14 of the control sleeve.

The forward end of the supporting sleeve 10 is formed with a conical bore and the forward portion of the control sleeve is slotted, as at 15, or otherwise formed, to provide a plurality of yieldingly contractile segments 16, the outer portions of these segments being formed with an inclined cam surface 17 complementary to the conical bore of the outer sleeve, whereby when the sleeve 11 is threaded into the supporting sleeve, the segments 16 are contracted to reduce the bore of the sleeve.

The forward end of the sleeve 11 is of cylindrical form and provided with knurling, as indicated at 18, so that the sleeve may be conveniently turned in the supporting sleeve 10. The sleeve 10 is wedged or formed adjacent its forward end with an indentation 19 causing displace-

2

ment of the metal within the thickness of the sleeve, and forming a projection 20 on the conical bore of the sleeve and extending axially thereof and being cooperable with the slots 15 in the pattern control sleeve to yieldingly retain the sleeve in adjusted position.

The sleeve 11 is bored to have a diameter substantially the same as the bore of the gun barrel. The threaded engagement between the sleeves is of such pitch relative to the incline surfaces 17 so that upon rotating the pattern control sleeve, the segments 16 are contracted to change the bore from full cylinder to full choke. The outer end face of the segments 16 may contain indicia, as shown in Figure 4, to visibly indicate the pattern for which the sleeve is adjusted, these indicia being applied to be read when the adjacent slot is engaged by the detent 20. The bore of the sleeve at the rear end thereof is of conical form, as shown at 21.

The outer sleeve 10 is preferably proportioned in length to provide an expansion chamber 25 intermediate the end of the barrel 12 and the sleeve 11, the sleeve being formed with a plurality of groups of elongated slots or apertures 26 to permit the escape of gas from the expansion chamber and effecting a substantial reduction in the recoil of the gun, as will be well understood. A sight 28 may be affixed to the outer sleeve 10.

It will be observed that my choke structure embodies only the inner and outer sleeves which are economical to produce, and the arrangement is such that without the use of tools, or the substitution of parts, the shot pattern can be conveniently adjusted over the entire range.

What I claim is:

1. A shotgun choke structure comprising an outer sleeve adapted to be secured to the muzzle of a shotgun barrel and being internally threaded intermediate its ends, a shot pattern control sleeve positioned in the forward end of said outer sleeve, said pattern control sleeve having its forward portion formed with yieldingly contractile segments extending outwardly from the forward end of said outer sleeve, said pattern control sleeve having its rear portion formed for threaded engagement with the outer sleeve, the forward end of said outer sleeve being formed with a conical bore and the forward end portions of said segments contiguous to said conical bore having inclined surfaces complementary to said conical bore and being cooperable to contract said segments when the pattern sleeve is threaded into said outer sleeve.
2. A shotgun choke comprising an outer sup-

porting sleeve adapted to be attached to the muzzle of the gun barrel and being threaded internally intermediate its ends, a pattern control sleeve threaded into the forward end of said supporting sleeve and extending outwardly from the forward end thereof, the forward portion of said pattern control sleeve being slotted to form yieldingly contractile segments having inclined surfaces cooperable with the forward end of said outer sleeve to contract said segments as the pattern sleeve is threaded into said supporting sleeve, and the forward end of said supporting sleeve contiguous to said inclined surfaces being formed with an integral detent rib engaging the slots of said pattern control sleeve.

3. A choke for shotgun barrels comprising an outer supporting sleeve formed at its rearward end for threaded engagement with a shotgun barrel and having an expansion chamber arranged forwardly of the muzzle of the barrel, said sleeve being formed with an internally threaded portion forwardly of said expansion chamber and having a portion extending forwardly of said threaded portion, said outer sleeve being formed with a conical bore at its forward end, a shot pattern control sleeve positioned in the forward portion

of said supporting sleeve and having threaded engagement at its inner end with the internally threaded portion of the outer sleeve to effect axial movement of the pattern control sleeve relative to said outer supporting sleeve, said pattern control sleeve being formed at its forward end with a plurality of yieldingly contractile segments extending forwardly from the forward end of said outer sleeve and having inclined surfaces cooperating with said conical bore upon axial movement of the pattern sleeve to effect radial movement of said segments.
